UNITED STATES PATENT OFFICE.

EVERETT R. BURTNELL, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed May 19, 1921. Serial No. 471,010.

To all whom it may concern:

Be it known that I, EVERETT R. BURTNELL, a citizen of the United States, residing at Los Angeles, in the county of Los Angeles and State of California, have invented new and useful Improvements in Internal-Combustion Engines, of which the following is a specification.

My invention relates to improvements in internal combustion engines of the type disclosed in my co-pending application, filed October 14, 1920, Serial No. 416,963; the principal objects of my present invention being to generally improve upon and simplify the construction of the engine disclosed in my application aforesaid, as well as other similar types of engines; to provide a construction wherein the head or upper portion of the cylinder is formed in a separate piece, thereby greatly facilitating and decreasing the cost of production of the engine and at the same time providing a construction that may be easily and quickly assembled and likewise easily and quickly removed for the purpose of repairs or adjustment of parts.

The type of engine to which my invention relates utilizes a sleeve valve and a piston valve for controlling the admission of gaseous fuel into the combustion chamber and for controlling the egress of burnt gases and products of combustion from said combustion chamber, and, necessarily, these valves are separated by an annular wall or partition.

It is one of the objects of my invention to provide a construction wherein this annular wall is formed integral with the removable headpiece, thereby permitting the valve cylinder to be readily bored and finished and likewise enabling the surfaces of the sleeve valve, the piston valve and the stationary wall or partition between them to be readily machined and finished, thereby providing a very accurate construction that is effective in minimizing leakage of fluid pressure.

With the foregoing and other objects in view, my invention consists in certain novel features of construction and arrangement of parts that will be hereinafter more fully

described and claimed and illustrated in the accompanying drawings, in which—

Fig. 1 is a vertical section taken through the center of an internal combustion engine 55 of my improved construction.

Fig. 2 is a side elevational view of the engine and showing the cover plate of the valve actuating and timing gear case removed.

Fig. 3 is a top plan view of the separately formed head that is positioned on the upper end of the cylinder block and with one end thereof in horizontal section.

Fig. 4 is a vertical section taken approximately on the line 4—4 of Fig. 3.

Fig. 5 is a horizontal section taken approximately on the line 5—5 of Fig. 4.

Fig. 6 is a plan view of the cylinder block of the engine.

Fig. 7 is a vertical section taken approximately on the line 7—7 of Fig. 6.

Fig. 8 is a horizontal section taken approximately on the line 8—8 of Fig. 7.

Referring by numerals to the accompanying drawings, which illustrate a practical embodiment of my invention, 10 designates the crank case of the engine, 11 the crank shaft, 12 the cylinder block in which are formed a power piston chamber 13 and a 80 valve chamber 14, said chambers being arranged side by side and of uniform diameter throughout their lengths, thereby enabling the boring and finishing operations to be readily performed.

The upper portion of the cylinder block is preferably provided with a water jacket 15, and arranged for reciprocatory movement within the chamber 13 is a piston 16 that is connected in the usual manner to 90 crank shaft 11.

Arranged for reciprocatory movement within chamber 14 is a sleeve valve 17 that is connected in the usual manner to a crank on a valve actuating and timing crank shaft 18, which latter is rotatably mounted in suitable bearings in the crank case 10 and being driven from shaft 11 in any suitable manner, preferably by means of a train of gearing 19.

The external diameter of the sleeve valve 17 is the same throughout its length and the

60

70

85

95

100

internal diameter of said valve is the same throughout the greater part of its length, thereby enabling said valve to be readily machined and finished.

- 5 Concentrically arranged within the upper portion of sleeve valve 17 and spaced apart therefrom, is a piston valve 20 that is connected in any suitable manner to the crank on shaft 18, and said piston valve co-operates 70
10 with the sleeve valve in controlling the admission of gaseous fuel into the combustion chamber of the engine and the egress or exhaust of burnt gases and products of combustion therefrom.

- 15 For a more detailed description of the construction and operation of the sleeve valve 17 and piston valve 20, reference may be had to my above mentioned co-pending application.

- 20 In the construction set forth in said co-pending application, the head or upper portion of the cylinder block is formed integral with the main body portion of said block, but in the present construction, this head is 80
25 separately formed and it is provided with an integral structure that serves as a cylinder for the upper portion of the piston valve and with a depending annular wall that serves as a partition between the upper portion 85
30 of the sleeve valve and the lower portion of said piston valve.

As illustrated, this removable head comprises a plate 21 that is hollow on provided with a chamber that communicates with the 90
35 water jacket of the cylinder block and said plate being secured in position on top of said cylinder block in any suitable manner, preferably by bolts such as 22.

- 40 Formed integral with the plate 21 and projecting upwardly therefrom, over the valve chamber 14, is a substantially cylindrical member 23 that is provided with a water jacket which communicates with the chamber in plate 21.

- 45 The chamber 24 within this cylindrical member 23 extends downwardly through plate 21 and through a depending annular wall or flange 25 that is formed integral with the underside of the plate, and said chamber 24 is of uniform diameter throughout its length, thereby permitting its internal surface to be readily bored, machined and finished.

This chamber 24 receives the reciprocating piston valve 20, and the depending wall or flange 25 which has the same external diameter throughout its length, fits snugly within the upper portion of sleeve valve 17.

- 50 In order to facilitate assembly and to insure the concentric arrangement of the annular wall or flange 25 within the upper portion of chamber 14, a concentric annular shoulder 26 is formed on the underside of plate 21 around the wall or flange 25 and the 100
55 diameter of said shoulder being such that

it fits snugly within the upper end of chamber 14 when the head is positioned on the cylinder block.

Annular wall or flange 25 is provided with one or more ports such as 27 that are 70
60 adapted to co-operate with the ports in sleeve valve 17 and piston valve 20 in controlling the admission of gaseous fuel to the combustion chamber of the engine and the exhaust of burnt products of combustion 75
65 therefrom.

Formed in the central portion of the plate 21 that forms the base of the head, is a horizontally disposed port or chamber 28, the inner end thereof communicating with the central portion of the piston valve chamber 24 in the removable head and the outer head of said port or chamber 28 being open on the underside of plate 21 and communicating with the upper end of piston chamber 85
70 13 when the head is properly positioned on the cylinder block.

Formed through the wall of plate 21, above this port or chamber 28, is a threaded aperture 29 that is adapted to receive the 90
75 threaded shank of a spark plug 30.

Removably positioned in the upper end of the piston valve chamber 24 is a breather valve that comprises a ring-shaped body portion 31 that fits snugly within said chamber 95
80 85 and said ring being provided with a plurality of partitions or deflecting plates 32 that occupy different vertical planes and which are disposed so as to form a tortuous 90
85 95 passageway for the air as it enters and discharges from the upper portion of the piston valve chamber.

The removable head contemplated by my invention is relatively simple in structure, may be easily and cheaply produced, and the surfaces that are engaged by the sleeve and piston valves are capable of being readily machined and finished, thereby making it possible to produce fluid tight joints between the working faces of said head and the co-operating sleeve and piston valves. Further, by providing a removable head, it is possible to easily and quickly gain access to the sleeve and piston valves in the event that the same require repair or adjustment.

It will be readily understood that minor changes in the size, form and construction of the various parts of my improved internal combustion engine may be made and substituted for those herein shown and described, without departing from the spirit of my invention, the scope of which is set forth in the appended claims.

I claim as my invention:

1. In an internal combustion engine, the combination with a cylinder block provided with a valve chamber having the same diameter throughout its length and concentrically arranged valves within said chamber.

- ber, of a removable head positioned on top of the cylinder block and provided with a chamber for one of said valves, and an annular wall formed integral with said head which annular wall extends downwardly into the valve chamber between the valves therein.
2. The combination with an internal combustion engine cylinder block having a valve chamber the diameter of which is uniform throughout its length, of a head removably applied to the top of the block for closing the valve chamber therein, said head being provided with a valve chamber that is concentrically disposed with respect to the valve chamber in the cylinder block, an annular wall extending from the underside of said head into the upper portion of the valve chamber in the cylinder block, the external diameter of said annular wall being uniform throughout its length and the internal diameter of said wall corresponding with the internal diameter of the valve chamber in said head, so that the internal diameter of the valve chamber in the head and the opening through said annular wall is uniform throughout the length of the combined chambers, and a concentric shoulder on the underside of said head, which shoulder is adapted to fit snugly within the upper end of the valve chamber in the cylinder block.
3. The combination with an internal combustion engine cylinder block having a piston chamber and a valve chamber, of a head removably positioned on top of said cylinder block and having a portion disposed within the upper end of the valve chamber, there being a valve chamber formed in said head and a concentrically arranged wall extending from the underside of said head downwardly into the valve chamber in the cylinder block, and the chamber within said annular wall being a continuation of the valve chamber in the head.

In testimony whereof I have signed my name to this specification.

EVERETT R. BURTNETT.
